(57) CLAIM

The ornamental design for a shaped applicator bottle, as shown and described.

DESCRIPTION

FIG. 1 is a rear perspective view of the shaped applicator bottle, a pump unit shown in phantom and forming no part of the invention hereof;

FIG. 2 is a right side view thereof;

FIG. 3 is a left side view thereof;

FIG. 4 is a front side view thereof;

FIG. 5 is a rear side view thereof;

FIG. 6 is a top view thereof; and,

FIG. 7 is a bottom view.

The broken line showing in FIGS. 1-4 & 6 is for illustrative purposes only and forms no part of the claimed design.
